UNITED STATES PATENT OFFICE.

NATHANIEL L. BRADLEY, OF WEST MERIDEN, CONNECTICUT, ASSIGNOR TO
BRADLEY & HUBBARD, OF SAME PLACE.

DESIGN FOR CALL-BELLS.

Specification forming part of Design No. **7,134**, dated January 27, 1874; application filed January 15, 1874.
[Term of Patent 14 years.]

To all whom it may concern:

Be it known that I, NATHANIEL L. BRADLEY, of West Meriden, in the county of New Haven and State of Connecticut, have invented a new Design for Call-Bells; and I do hereby declare the following, when taken in connection with the accompanying drawing and the letters of reference marked thereon, to be a full, clear, and exact description of the same, and which said drawing constitutes part of this specification, and represents a side view.

This invention relates to a design for what are known to the trade as call-bells—that is, such as are sounded by depressing a piston arranged through the top of the bell; and the design consists in a tripod, in the apex of which the bell is suspended, and above the

apex the piston-knob by which the bell is struck.

A B C are three posts standing inclined to and crossing each other, and attached together at the crossing, the upper ends running up above the crossing. At the crossing the bell D is suspended, and above the piston-knob E, by depressing which the bell is sounded.

I claim as my invention—

The design for call-bell, as herein described, and shown in the accompanying illustration.

N. L. BRADLEY.
